STOVE

Bernard Field, Brookline, Mass.

Application November 2, 1932, Serial No. 640,787

2 Claims. (Cl. 126—36)

This invention relates to improvements in stoves and particularly to an oven structure for combination stoves that are adapted to utilize either wood, coal, oil, or gas, as fuel.

5 The object of the invention is to provide a stove of the type mentioned with an oven in which a gas burner may be mounted and operatively connected to its source of fuel supply without altering the bottom flue structure usually provided in coal stoves.

Another object of the invention is to provide an improved gas burner and baffle plate therefor mounted one upon another and adapted to be handled as a unit, it being possible to disconnect the burner from the gas supply pipe without the use of tools and remove the baffle plate and burner in unison from the oven when coal is to be used in the stove as fuel, although these members may remain in position within said oven if it is so desired.

Still another object of the invention is to provide a novel structure of baffle plate which is so associated with the gas burner that a perfect circulation of the heat within the oven will be assured.

Still another very important object of the invention is to so position the mixing chamber with relation to the fuel entrance orifice to the burner that a safe connection will always be made between these parts when the baffle plate is pushed to its correct position in the oven, it being assured that the baffle plate will always be guided to its correct position by the engagement of the sides of the baffle plate with guide portions provided at the sides of the oven and by the engagement of the oven door with the front of the baffle plate when the oven door is closed.

The stove, furthermore, embodies in its construction an auxiliary flue for the oven, which is connected with the main flue of the stove and is provided with a trap door which is opened when gas is utilized as a fuel. An auxiliary air inlet, suitably baffled, is provided upon the oven door, the amount of air entering the oven through this inlet being regulated by a slide.

The invention consists in an improved stove structure as set forth in the following specification and particularly as pointed out in the claims thereof.

Referring to the drawings:—

Fig. 1 represents a horizontal sectional view of the oven portion of a stove illustrating my improved gas burner and baffle plate therefor mounted therein.

Fig. 2 is an enlarged detail vertical section taken on the line 2—2 of Fig. 1.

Fig. 3 is a vertical sectional elevation through a portion of a stove and is taken on the line 3—3 of Fig. 1.

Fig. 4 is an enlarged detail vertical section taken on the line 4—4 of Fig. 1.

Fig. 5 is an enlarged front elevation of a portion of an oven door illustrating the auxiliary air openings provided therein, together with the means for controlling the amount of air passing through said openings.

Like numerals refer to like parts throughout the several views of the drawings.

In the drawings, 6 is a stove of a type adapted to utilize wood, coal, oil or gas as fuel and commonly called a combination stove. The stove 6 embodies therein a baking oven 7 provided with an upper wall 8, a lower wall 9, a rear wall 10, side walls 11 and a front door 12.

As this invention resides principally in the oven structure and portions of the stove associated therewith, the remaining portions of the stove are broken away in the drawings to save space.

Located between a top 13 for the stove 6 and the upper wall 8 of the oven 7 is a flue 14 which connects with a flue 15 which, in turn, is adapted to be connected in a well-known manner with a suitable chimney. Other flues 15' and 16 are located beneath the lower wall 9 of the oven 7 and all of the flues communicate with each other in a well-known manner to permit the heat and products of combustion to circulate around the oven before they eventually pass from the stove into the chimney through the flue 15.

Permanently mounted at the rear of the stove 6 upon the wall 10 thereof is a mixing member 17 provided with a fuel mixing chamber 18 therein. The mixing member 17 projects through an opening provided therefor in the wall 10 of the stove and has a tubular portion 19 formed thereon which is provided with a discharge orifice 20. A gas supply pipe 21 is connected to the mixing member 17 and discharges gas into the mixing chamber 18 in a well-known manner. The rear wall of the mixing member 17 is provided with the usual air inlet orifice 22 in front of which is a plate 23 which is adapted to be adjusted in a well-known manner to regulate the amount of air which may enter the mixing chamber through the orifice 22.

Positioned within the oven 7 in longitudinal alignment with the median line of the mixing member 17 is a gas burner 24 which is secured to and supported beneath a baffle plate 25 which, in

turn, is slidably mounted upon and supported by a plurality of lugs 26 which are provided upon the side walls 11 of the oven. The mixing member 17 is so positioned upon the wall 10 of the oven 5 that when the gas burner 24 is operatively connected thereto that said burner will be located a short distance above the upper surface of the bottom 9 of the oven. The gas burner 24 has a rear extremity 27 which is provided with a recess 28 10 into which the tubular portion 19 of the mixing member 17 projects, and the front extremity of said mixing member 17 abuts against a shoulder 29 which is provided within the recess 28. When the gas burner 24 and mixing member 17 15 are correctly positioned with relation to each other, the discharge orifice 20 of the mixing member will discharge the fuel directly into an inlet orifice 30 provided in the burner 24 and a safe connection will be made between the member 17 and burner 24.

The burner 24 is preferably forked and has a pair of parallel furcations 31 embodied therein and rows of gas discharge orifices 32 are provided in the opposite side walls of said furcations. 25 When the gas fuel is ignited the jets of flame are projected laterally in approximately a horizontal plane from the opposite side walls of the furcations 31.

The baffle plate 25, upon which the burner 24 30 is supported, embodies therein an outer baffle member 33 which is rectangular in form and is provided with a centrally disposed rectangular opening 34. The baffle member 33 has a flange 35 embodied therein which extends around the opening 34, said flange being formed in such a manner that a depression 36 will be provided in said baffle plate. A rectangular plate 37 is located in the depression 36 and is supported upon the flange 35. The edge portions of the plate 37 are 35 folded beneath the plate in a manner to clamp a sheet of insulating material 38 beneath said plate. The plate 37 with the insulation 38 secured thereto and another plate 39 are secured together and to the outer baffle member 33 by a plurality of bolts 40. A narrow space is provided 40 between the edges of the plate 37 and the adjacent faces of the depression 36 to allow for proper expansion and contraction between these parts.

Rows of suitable apertures 41 are provided at 45 the sides of the baffle member 33 and other apertures 42 are provided at the front of said baffle member. Another opening 43 is provided at the front of the baffle member 33 thereby forming a handle portion 44 which may be grasped by the 50 hand when the baffle plate 25 and burner 24 are being inserted in or removed from the oven. The rear portions of the opposite side edges of the baffle member 33 are curved at 45 for the purpose of engaging curved guide surfaces 46 which are 55 provided at the rear of the side walls 11 of the oven, so that when the baffle plate 25 is inserted in the oven and pushed rearwardly therein that said baffle plate will be guided into its correct position with relation to the mixing member 17. 60 The baffle plate 25 is furthermore so constructed that a front edge 47 thereof will be engaged by a rear edge portion 48 of the door 12 when the latter is closed and the interengagement of these members will cause the baffle plate 25 and burner 24 supported thereon to be correctly positioned 65 with relation to the mixing member 17.

As an aid in igniting the gas at the burner 24, orifices 49 are provided in the upper wall of the furcations 31 of the burner at a point adjacent to the forward extremity of said furcations,

see Fig. 1. An aperture 50 is also provided in the baffle member 33. The orifices 49 in the burner and aperture 50 in the baffle member 33 are connected with each other by means of a T-shaped guide member 51 provided with a groove 52 in its under surface, through which a small quantity of gas may be conducted from the burner to the aperture 50 where the gas may be ignited and the flame therefrom will communicate through the groove 52 with the gas emerging 10 from the orifices 32 of the burner.

As an aid in obtaining proper combustion of the gas fuel at the burner 24, an auxiliary air supply is obtained through the door 12, there being a plurality of apertures 53 provided therein at a point adjacent to the bottom of said door. 15 A slide 54 is mounted upon the rear of the door having apertures 55 provided therein which are adapted to align with the apertures 53, and the amount of air which is permitted to enter the 20 oven through the apertures 53 is regulated by moving the slide 54 to vary the effective area of the openings 53. A handle 56 is provided for the slide 54. A baffle member 57 is secured at the rear of the door above the slide 54 and is positioned to deflect the air entering the oven through said slide toward the bottom of the oven.

An auxiliary flue 58 is provided at the rear of the oven and adjacent to the top thereof where communication may be had with the flue 30 15, and a trap door 59 actuated by a handle 60 is so positioned that the fumes and other products of combustion may pass from the oven 7 through the flue 58 and into the flue 15 when the gas burner 24 is being utilized to heat the oven. 35 At this time the door 59 is held in its uppermost position by means of a notched portion 61 of the handle which engages the top 13 of the stove. When the burner 24 is not used to heat the oven the door 59 is located in the closed position 40 illustrated in Fig. 3.

When some material other than gas is to be used as a fuel for heating the oven 7, the gas burner 24 may be removed from the oven if it is so desired by opening the door 12 and grasping 45 the handle portion 44 of the baffle member 33 and the entire baffle plate 25 with the burner 24 mounted thereon may be removed in unison from the oven. Each time that the baffle plate and burner are inserted in the oven, the baffle plate 50 25 is slid rearwardly upon the lugs 26 until the shoulder 24 of the burner engages the extremity of the mixing member 17.

During the rearward movement of the baffle plate 25 in the oven the curved edges 45 of the baffle member 33 will engage the curved surfaces 46 provided at the sides of the oven and the burner will be guided so that the cylindrical portion 19 of the mixing member will enter the recess 28 of the burner and correctly align the burner and mixing member one with another.

If it so happens that the baffle plate 25 and burner 24 are not forced rearwardly in the oven so that a proper engagement is made between the burner and mixing member, when the door 65 12 is closed the rear edge 48 of said door will engage the front edge 47 of the baffle plate and force the latter rearwardly to its normal position.

The gas fuel is ignited by applying a match at the orifice 50 after the usual gas cock has been 70 actuated to supply gas to the burner.

The various apertures 41 and 42 are positioned in the baffle member 33 so that a perfect circulation of the heat within the oven will be assured, and the apertures 53 in the oven door and baffle 75

member 57 are so positioned that a perfect combustion of the gas fuel will always be obtained.

I claim:

- 5 1. A stove of the character described having, in combination, an oven, the side walls of which curve inwardly at the rear end thereof, a fuel mixing member mounted thereon, a gas burner and baffle plate therefor mounted one upon another within said oven and movable as a unit into and out of operative relation to the fuel mixing member, means to guide said burner relatively to the mixing member, a door for the oven adapted to engage the baffle plate and move the latter to always position the burner at the same location relatively to the mixing member when the door is closed, 10 and out of operative relation to the fuel mixing member, the side edges of said baffle plate curving inwardly at the rear end thereof and cooperating with the curved side walls of said oven, to guide said burner relatively to the mixing member, and a door for the oven adapted to engage the baffle plate and move the latter to always position the burner at the same location relatively to the mixing member when the door is closed. 15
2. A stove of the character described having,

in combination, an oven, a fuel mixing member mounted thereon, a gas burner and baffle plate therefor mounted one upon another within said oven and movable as a unit into and out of operative relation to the fuel mixing member, means to guide said burner relatively to the mixing member, a door for the oven adapted to engage the baffle plate and move the latter to always position the burner at the same location relatively to the mixing member when the door is closed, means to provide an auxiliary air supply for the burner through said door at the approximate level of the burner, means to regulate said auxiliary air supply, and a baffle plate fast to said door adjacent to the means for providing an auxiliary air supply for the burner and adapted to deflect said air toward the bottom of said oven and around said burner.

BERNARD FIELD.
